Primary Examiner — Richard E Chilcot(74) *Attorney, Agent, or Firm* — Aslan Law, P.C.(57) **CLAIM**

The ornamental design for a sanding and polishing machine, as shown and described.

DESCRIPTION

FIG. 20.1 is a first perspective view of a sanding and polishing machine showing my new design;
 FIG. 20.2 is a right side view thereof;
 FIG. 20.3 is a front view thereof;
 FIG. 20.4 is a left side view thereof;
 FIG. 20.5 is a rear view thereof;
 FIG. 20.6 is a top view thereof; and
 FIG. 20.7 is a bottom view thereof.
